Frank G. Brakke Inventor

UNITED STATES PATENT OFFICE.

FRANK G. KRAKAN, OF PITTSBURGH, PENNSYLVANIA.

RADIATOR.

Application filed July 13, 1921. Serial No. 484,324.

To all whom it may concern:

Be it known that I, FRANK G. KRAKAN, a citizen of the United States, residing at Pittsburgh, in the county of Allegheny and 5 State of Pennsylvania, have invented certain new and useful Improvements in Radiators, of which the following is a specification.

This invention relates to improvements in 10 radiators and more particularly to an improvement on the structure shown and described in my co-pending application filed March 31, 1921 and bearing Serial #457,206.

15 The object of the present improvement resides chiefly in taking care of the over supply of water which does not find its way out by way of the water tubes.

20 The invention further aims to provide an improved structure for the lower part of the radiator whereby an efficient exit for the water is provided so arranged as to permit nothing but water to pass through from the radiator, thus preventing a material loss 25 of steam.

Other objects of the invention will appear upon consideration of the following detail description and accompanying drawings, wherein:

30 Figure 1 is a front elevation of the radiator partly broken away to expose the improved structure.

Figure 2 is a side view, also partly broken away to illustrate the barrier plate in side 35 elevation,

Figure 3 is a detail perspective view of the barrier plate, and

Figure 4, is a horizontal sectional view taken on line 4—4 of Figure 1.

40 Referring to the drawing by numerals, the radiator 1 is provided with the lower water compartment 2 which is relatively shallow and which is provided with side walls 3 extending across the width of the radiator, and these walls 3 are provided with a series of holes or other suitable openings 4, the holes being arranged in the center of the wall, that is midway between the upper and lower edges thereof. In the 45 present instance, four openings are provided in each wall but it will be obvious that any number may be provided to suit conditions.

50 Soldered or otherwise suitably secured to the inner surface of each wall 3 is a barrier plate 5 shown in detail in Fig. 3 of the

drawing, which consists of an attaching flange 6 and an angularly disposed strip 7. This flange 6 is adapted to be secured to the inner surface of each wall 4 near the upper edge thereof so that the angular strip 7 will 60 overlie the openings 4, the plate being fastened in a manner that will cause the lower edge 8 of the angular strip 7 to be very slightly raised above the bottom of the compartment 2 thus permitting the water to 65 pass beneath the barrier plate so that the overflow of water may be emitted from the openings 4. A constant level of water will be maintained in the compartment due to the central position of the openings 4, and 70 any excess of water will be readily emitted through the openings.

In order to protect the tubes of the radiator against injury, I preferably provide a 75 housing 9 which is provided with a plurality of perforations such as slots 10 to allow for the free circulation of air around said tubes.

In operation steam is admitted to the condenser through the inlet nipple 11 and enters chamber 12, after which it passes downwardly through the rear set of condensation tubes 13 into the condensation chamber 14. Any condensation accumulates in the chamber 14 to a level with the openings 4 after 80 which it flows outwardly into the outlet chamber 15. The uncondensed steam is prevented from flowing through the openings 4 by means of the baffle plates 5 and consequently its only escape is upwardly 85 through the forward set of condensation tubes 16, the upper ends of which open into the chamber 17 which communicates with the outlet chamber 15 through the side passages 19. Obviously any condensation occurring into the tubes 16 will settle back 90 into the chamber 14. In order that the water of condensation may be removed, an outlet nipple 20 is associated therewith as illustrated in the drawing. 95

100 Minor changes may be made in the details of construction without departing from the spirit of the invention and the scope of the claims hereunto appended.

105 What is claimed is:

1. A radiator comprising a relatively shallow lower compartment provided in each of its side walls with a series of exit openings, an upper compartment associated therewith, tubes connecting the compartment 110

2
ments to provide heat radiating means, a barrier plate secured to each of the side walls above the openings therein and disposed as an angle with respect to the vertical position of the side walls so that said angular plate will extend across the openings in spaced relation thereto and a jacket inclosing the top, sides and bottom of the radiator.

10. 2. A radiator comprising a casing, a relatively shallow compartment adjacent the lower end of the casing, a compartment adjacent the upper end of the casing, fluid conducting tubes connecting the compartments, the side walls of the lower compartment being vertically disposed and provided with a series of openings located between the

upper and lower edges of the walls, a barrier plate attached to the inner surface of each wall, each barrier plate comprising an attaching flange secured adjacent the upper edge of each wall, and an angular strip carried by the attaching flange and disposed at an angle to its respective wall, the said strips overlying the openings in the walls, and having their lower edges slightly spaced from the bottom wall of the compartment.

In testimony whereof, I have affixed my signature in the presence of two witnesses.

FRANK G. KRAKAN.
